WILLIAM BENDER, OF DOWNERS GROVE, AND PAUL HOFFMAN, OF WESTERN SPRINGS, ILLINOIS, ASSIGNORS TO RAMAPO AJAX CORPORATION, OF NEW YORK, N. Y., A CORPORATION OF NEW YORK.

ANTICREEPING GUARD-RAIL CLAMP.

Application filed January 27, 1923. Serial No. 615,212.

To all whom it may concern:

Be it known that we, WILLIAM BENDER, a citizen of the United States, and resident of Downers Grove, county of Du Page, State of Illinois, and PAUL HOFFMAN, a citizen of the United States, and resident of Western Springs, county of Cook, State of Illinois, have invented certain new and useful Improvements in Anticreeping Guard-Rail Clamps, of which the following is a specification.

This invention relates to improvements in guard rail clamps for holding a main or traffic rail and a guard rail in adjusted position relative to each other, and relates particularly to an improved structure which will resist great pressures without distortion and which will also act as an anti-creeping device.

The invention more specially relates to a guard rail clamp for track rails that will possess the necessary rigidity and strength to resist the strains imposed by traffic, but which will permit a certain limited adjustment to the wave motion of the track without any of the parts of the clamp structure becoming loose or displaced with respect to each other.

The invention further relates to a construction in which the parts may be aligned and assembled with a minimum amount of machine work upon the parts to fit them together.

Various other features of the invention will be in part obvious from an inspection of the accompanying drawings and in part will be more fully set forth in the following particular description of one form of mechanism embodying the invention, and the invention also consists in certain new and novel elements of construction and combination of parts hereinafter set forth and claimed.

In the accompanying drawings,

Figure 1 is a plan view of our improved guard rail clamp in its adjusted position;

Figure 2 is a side elevation of the same, showing the rails in section;

Figure 3 is a detail view showing a section through the clamp plate; and

Figure 4 is a detail section on line 4—4 of Figure 2.

In the particular embodiment of the invention shown in the accompanying draw-

ings, the clamp plate 1 is provided with a central recess or seating space for the track rail 2 and the guard rail 3, and partially encloses the same. The entire periphery of the clamp plate is outlined by a fillet of reinforcing metal 4. This reinforcement is appreciably thicker around the periphery of the recess than around the outer periphery of the plate. The ends of the recess provide upright abutments 5 and 6, and this reinforcing metal at the bottom of the recess forms a supporting head 7. The bottom of the clamp plate is also flared or tapered outwardly, approximately in the middle line of the plate beneath the recess, as at 8, so as to give the plate its maximum width at this point.

The track rail and the guard rail, instead of resting directly upon the supporting head provided at the bottom of the recess, are supported upon a bead or projection which extends lengthwise of this supporting head, and provides a narrow bearing 9 for the bases of the rails, making substantially a line contact therewith. A similar bead or projection 9^a, preferably a continuation of the bearing 9 is provided centrally of the abutment 5. The face of this abutment is oppositely tapered as at 10 from the line of the bead or projection, forming approximately a V-face. The opposite abutment 6 is planed or machined so as to provide a flat or squared bearing face. Both of these abutments may be inclined in the usual manner, and preferably the thickest portion of the fillet of reinforcing metal is at the corners of the abutments.

A spacing block 11 is provided between one of the rails and the abutment 5, and is formed with an oppositely tapered recess 12 to seat the abutment, and is also formed with a groove 14 centrally thereof to receive and interlock with the projection 9^a that is formed on said abutment. A spacing block 15 is likewise provided between the other rail and the abutment 6. This block is preferably wedge shaped longitudinally, so it can be driven home against the sloping face of the abutment 6 and force the parts of the structure together. Preferably this block is provided with an integral flange 16 which passes through a slot in the abutment 6. After the wedge block has been driven in position any well-known or conventional

means, such as the cotter pin 17, may be employed to hold the wedge block in position. The rails are spaced from each other by adjustable filler blocks 18, which may be 6 serrated along a diagonal line, whereby suitable adjustment of these blocks may be effected. Suitable guard pins 19 may be formed integral with the filler blocks, which rest on opposite sides of the clamp plate 10 and hold the filler blocks from displacement.

By means of this construction the bases of the track rails seat upon a relatively narrow bearing, which will permit a limited 15 tilting or swinging movement of the clamp plate with reference to the rail bases without longitudinal movement of the clamp relative to the rails. This allows for a certain amount of movement of the track 20 or wave motion of the road-bed without disturbing the relative position of the clamp structure. Consequently there is little or no shifting of the parts of the clamp with respect to each other or with respect to 25 the rails, and consequently the shape of the clamp plate causes the same to operate as an anti-creeping device for the track rails by abutting the ties. The engagement of the tapered abutment in 30 the beveled recess permits some slight play without in any degree impairing the strength and rigidity of the structure to resist the thrust of traffic. At the same time this arrangement will hold this spacing 35 block against displacement, even though the projecting edges thereof which form lugs or ears embracing the abutment and ordinarily would assist in holding the block in place, should be broken through an accidental blow or in any other manner. This 40 arrangement of the parts, together with the placing of the reinforcing fillet around the periphery of the plate, provides a very strong construction that will resist the most 45 extreme pressures to which it is subjected in operation without distortion or without displacement of the parts.

Having thus described our invention, we claim:

50 1. In a guard rail clamp for a traffic rail and a guard rail, the combination of a clamp plate provided with abutments to receive the side thrust from the rails and having a bearing for the bases of said rails, said bearing comprising a projection integral with the clamp plate extending lengthwise of the supporting portion of the plate and transversely of the rails thereby to permit a limited tilting movement of the plate 55 without changing the line of contact of said bearing, and means for holding said rails in engagement with said bearing.

60 2. In a guard rail clamp, the combination of a clamp plate provided with a supporting head for the main rail and guard rail

and with upright abutments to receive the side thrust from the rails, a relatively narrow projection extending lengthwise of the supporting head to form a bearing for the rails and extending across one of said abutments, and spacing blocks between said rails and the abutments, one of said blocks being provided with a groove to receive the projection formed on one of the abutments. 70

3. In a guard rail clamp, the combination of a clamp plate provided with a supporting head for the main rail and guard rail and with upright abutments, a relatively narrow projection extending lengthwise of the supporting head to form a bearing for the rails and extending across one of said abutments, spacing blocks between said rails and the abutments, one of said blocks being provided with a groove to receive the projection formed on one of the abutments, and 80 the other abutment having a squared face to engage with a wedge surface on the other block, and means to hold said rails and blocks in adjusted position. 85

4. An anti-creeping guard rail clamp for a guard rail and traffic rail, comprising a clamp plate provided with upright abutments and having a relatively narrow bearing for the rails between the abutments permitting a tilting movement with relation to the rails, spacing blocks between said rails and abutments, and means to hold said rails and blocks in adjusted position. 90

5. An anti-creeping guard rail clamp for a guard rail and a traffic rail, comprising a clamp plate provided with upright abutments and having a relatively narrow bearing for the rails between the abutments, spacing blocks between said rails and abutments, one of said abutments having a tapered face to engage in a corresponding recess provided in one of said blocks, and means to hold said rails and blocks in adjusted position. 95 100

6. An anti-creeping guard rail clamp to hold the guard rail and traffic rail in spaced relation, comprising a clamp plate provided with upright abutments and having a relatively narrow bearing for the rails between the abutments, and spacing blocks between said rails and abutments, one of said abutments having a tapered face to engage in a corresponding recess provided in one of said blocks, and the other abutment having a squared face to engage with a wedge surface 105 110 on the other block. 115

7. An anti-creeping guard rail clamp to hold the guard rail and traffic rail in spaced relation, comprising a clamp plate provided with upright abutments and having a bearing for the rails between the abutments, spacing blocks between said rails and abutments, one of said abutments having a projecting bead extending up the face of the same to engage in an interlocking recess 120 125 130

provided in one of said blocks, and the other abutment having a squared face to engage with a wedge surface on the other block, and means to hold said plate and rails in adjusted position.

8. An anti-creeping guard rail clamp to hold the guard rail and traffic rail in spaced relation, comprising a clamp plate provided with abutments to receive the side thrust from the rails and having a relatively narrow bearing for the rails between the abutments, spacing blocks between said rails and abutments, one of said abutments having a projection to interlock with one of the spacing blocks, and means to hold said rails and blocks in adjusted position.

9. In an anti-creeping guard rail clamp for track rails, the combination of a clamp plate having a recess therein to receive the main rail and the guard rail, the periphery of said clamp plate being outlined by a fillet of metal, said fillet being thicker around the border of the recess, the ends of said recess comprising abutments to receive the side thrust from said rails, and the bottom of said plate being tapered outwardly to provide a maximum width of the plate adjacent the middle line thereof, and means for securing the clamp plate to said rails and spacing the rails therein.

10. In an anti-creeping guard rail clamp for track rails, the combination of a clamp having a recess therein to receive the main rail and the guard rail, the periphery of said clamp plate being outlined by a fillet of metal, said fillet being thicker around the border of the recess and forming a supporting head having a projection integral therewith to contact with the bases of said rails, the ends of said recess comprising abutments and the bottom of said plate being tapered outwardly to provide a maximum width of the plate adjacent the middle

line thereof, and means for securing the clamp plate to said rails.

11. In an anti-creeping guard rail clamp for track rails, the combination of a clamp plate having a recess therein to receive the main rail and the guard rail, the ends of said recess comprising abutments, one of said abutments having an upright central projection and being beveled transversely to the length of the said projection and the other abutment having a flat surface, a spacing block provided with a beveled recess and a groove to receive said projection on one abutment, and a spacing block having a wedge surface to engage the other abutment.

12. In an anti-creeping guard rail clamp for track rails, the combination of a clamp plate having a recess therein to receive the main rail and the guard rail, the periphery of said clamp plate being outlined by a fillet of metal, said fillet being thicker around the border of the recess and forming a supporting head having a projection integral therewith to contact with the bases of said rails, the ends of said recess comprising abutments to receive the side thrust from said rails, one of said abutments having a central projection and being oppositely tapered therefrom and the other abutment having a flat surface, a spacing block provided with a beveled recess and a groove to receive said projection on one abutment, and a spacing block having a wedge surface to engage the other abutment, the bottom of said plate being tapered outwardly to provide a maximum width of the plate adjacent the middle line thereof.

Signed at Chicago, in the county of Cook and State of Illinois, this 22nd day of January, A. D. 1923.

WILLIAM BENDER.
PAUL HOFFMAN.
